UNITED STATES PATENT OFFICE.

WILLIAM H. DANA, OF COLUMBUS, OHIO.

DESIGN FOR AN IRONING-BOARD.

SPECIFICATION forming part of Design No. 28,202, dated January 18, 1898.

Application filed November 26, 1897. Serial No. 659,923. Term of patent 7 years.

To all whom it may concern:

Be it known that I, WILLIAM H. DANA, a citizen of the United States, residing at Columbus, in the county of Franklin and State of Ohio, have invented and produced a new and original Design for Ironing-Boards; and I do hereby declare the following to be a full, clear, and exact description of the same, reference being had to the accompanying drawings, forming a part thereof.

In the drawings, Figure 1 is a perspective view of an ironing-board embodying my design. Fig. 2 is an edge elevation. Fig. 3 is an end view looking to the left, as shown in Fig. 2; and Fig. 4 is a bottom plan view.

Like characters of reference in the different views designate corresponding parts.

A designates the largest of the boards, which is shown to be substantially rectangular in form, and B and C are two smaller boards of slightly-tapering form. The board B is shown to be larger than the board C, and both these

smaller boards A and B are supported by a standard or bracket D upon one side of the largest board A. The boards B and C are shown to stand parallel to the board A, with the smaller end of one adjacent the larger end of the other.

The important feature of my design for an ironing-board resides in a large board A, with smaller tapering boards B and C supported on one side of the large board A, the two smaller boards being arranged so that the small end of one lies adjacent the larger end of the other.

What I claim is—

The design for an ironing-board, substantially as herein shown and described.

In testimony whereof I affix my signature in presence of two witnesses.

WILLIAM H. DANA.
